RETRIEVABLE WIRE LINE BRIDGE PLUG

Carl E. Strom, South Gate, Calif.

Application May 24, 1939, Serial No. 275,407

8 Claims. (Cl. 166—13)

This invention relates to devices used for facilitating work in deep wells, particularly, facilitating work against frequently experienced difficulties, due to encountered natural matters and pressures.

One of the objects of this invention is to provide means useful for operations not dependent on, or subject to, obstructive natural conditions, or forces, in a well.

10 Another object is to provide operating means that may be released, or utilized at will, regardless of natural conditions in the well.

Another object is to provide an apparatus that will operate with, or by, or independently of any 15 operating medium in a well.

Another object is to provide an apparatus that can be prepared for predetermined operations in the well before the apparatus is lowered into the well.

20 Another object is to make equipment used in a well more reliable regardless of conditions in the well.

Another object is to make equipment effective while in the well and easily retrievable when 25 not further required in the well.

Other objects will appear from the following description and appended claims as well as from the accompanying drawing, in which—

Fig. 1 is a fragmentary longitudinal midsectional view of a device designed to operate according to the present invention, shown in a portion of well casing, a portion of the device being shown uncut, to show the outside appearance.

Fig. 2 is a cross section on line 2—2 of Fig. 1.

35 Fig. 3 is a cross section on line 3—3 of Fig. 1.

Fig. 4 is a slightly modified form of operating-force-holding parts in a fragmentary illustration of somewhat reduced scale.

40 Fig. 5 is a fragmentary detail illustration of a temporary shut-off-means for the operating conduits in cases of cementing below the device.

All sorts of equipment and tools are used in wells for all sorts of purposes, and many of such things must operate at a considerable distance 45 away from, and absolutely out of sight or proper observation of the operator.

On the other hand, though science may have given information enabling an operator to cope with various conditions in a well, there are nevertheless still uncertain factors encountered against which an operator has to use powerful devices.

For one thing, it is well enough known that certain forces that exist in various stratum, or strata, may be made use of for some operations.

55 On the other hand, such forces are more gen-

erally only obstructive to an operator and his equipment.

The obstructive forces are at times so great that it becomes necessary to shut off such forces at suitable levels, to enable the operator to advance properly with his work below or above such levels.

At times it becomes necessary to cement off a certain individual stratum, in order to shut off water or other mediums that may interfere later on with other operations. In such a case it is 10 merely a matter of getting the proper cementing medium to that particular stratum, letting the medium harden, to then continue with drilling or other operation through the medium.

At other times, however, it is desirable to merely hold off any matter below a certain level, or stratum, in order to allow for a proper operation of certain work above such level without any cementing, that would naturally have required extra work after the said operation has been 20 accomplished satisfactory, after which a further downward operation might be desirable or required.

The present invention provides for either possibilities with equally efficient assurances towards 25 desirable success.

As illustrated in Fig. 1, equipment of the type referred to is generally applied through a well casing, as indicated at 11.

In this illustration, however, the device is 30 particularly designed to preferably operate as a bridge-plug only, for and in cases where work above the bridge is to be done under the protection of the bridge-plug.

In such a case, any matter below the level at 35 which work is to be done is just naturally to be shut off, and consequently it is not particularly practical to make use of the force of such matter for any operating purposes.

As a rule, an operating force is in such cases 40 applied from the surface level, through the well casing 11, to act upon any inserted equipment.

With the present invention, an operating force is preferably provided right within the equipment.

At shallow depth, and in cases where no particular danger is involved, such an operating force may be provided by carbide-gas, or acetylene, taking proper care that excessive pressure is allowed to escape by suitable safety-valves, such a possibility being roughly outlined in Fig. 4. The container 12 is for that purpose designed to hold the carbide. A valve 13 opens access of water to the carbide and at the same time permits the developed gas to escape towards any co-operatively connected equipment, as will be described later 50 55

on. A suitably designed safety valve 14 reduces danger. The surrounding housing 15 of any co-operating equipment is provided with an inlet valve 16 for water to enter the housing 15 and 8 the carbide-container 12, the apertures 17 serving as communication between the container and the equipment-housing.

In some cases, compressed air may be sufficient and desirable to operate through a mechanism 10 illustrated in Fig. 4.

At greater depth, and under generally dangerous conditions of deep well, particularly, oil-wells, other means should preferably be provided.

Not saying that other mediums could not be 15 used, nor that science may develop more suitable means, a hydrogen-methane-ethane-gas may be found quite suitable for the purpose to operate a device as illustrated in Fig. 1.

Hydrogen (H), methane (CH_4), and ethane 20 (C_2H_6), will provide a suitably high pressure of 5000 pounds, or more, to operate against generally encountered pressures in a well.

Such a pressure force may well be stored in a container 12a, disposed within the central 25 tubing, or housing 15a of an equipment that may be useful for various purposes in a well, such as tube-cutting, reaming, or cementing. A control-valve 13a extends upwardly, to be actuated by a so-called "go-devil", as indicated at 18, slid- 30 ingly disposed over the well-tool wire-line 19.

At the proper moment, when the equipment is at the desired level and under the proper condition, the "go-devil" may be released to descend along the wire-line to act on the control-valve 35 13 or 13a.

Once the control-valve 13 or 13a is released, gas will escape from the container 12 or 12a.

In Fig. 4, the control-valve 13 is merely provided with the reduced portions 20, to move 40 sufficiently for opening the container for the escape of gas; while, in Fig. 1, the control-valve 13a is provided with well-defined valve-portions 13b to seat upon similarly, or correspondingly well-defined seats 21 on the container 12a.

45 Though it may be found most practical to have the container in form of an independent part, merely inserted into the equipment, in conjunction with which it is to be used; but, it should be understood that a pressure-holding 50 chamber may readily be provided directly in the equipment, as a cavity worked, or machined into the equipment. The retrievable wire line bridge plug is provided with a lower-end closing cap 22, and an upper-end handling cap 23, between which the container 12a is firmly held by means of the spider-webbed insertions 24 and 25.

As illustrated, while the upper spider 25 is 60 below the upper handling-cap 23, the spider is not directly contacting the cap 23 an inner crosshead 26 being inserted in the upper end of the inner tubing or housing 15a, the crosshead serving as a securing means for the wire-line 19.

65 Though bridge-plugs are frequently lowered into a well by means of operating tubing, the handling takes considerable time and labor inasmuch as additional lengths of tubing have often and repeatedly to be attached before any equipment reaches the operating level, and then it takes just about as long until all the tubings have been withdrawn from the well before any actual work above the inserted plug can be begun.

75 The lowering of any equipment, or tool, by

wire-line is so much more desirable for many reasons, and any equipment, provided with means of the present invention can be handled by wire-line.

When such equipment, or tool, is brought to the 5 point of operation, a suitably applied jerk will shear off the pin 27 after which the wire-line can quickly be withdrawn from the well, leaving the equipment in the well at the point of operation.

Particularly, a bridge-plug of the type illustrated in Fig. 1 can be lowered to the point of operation by the wire-line, then set by the operation of the control-valve as described herebefore, to remain in the well until to be removed. 15

When the pressure medium escapes from the 20 container, it passes through the conduits 28 to act on the plungers 29 which, in turn, act on the packing material 30 until the packing material expands to the point of wedging itself against 25 the inside wall of the well-casing 11, the embedded metal-pieces 33 helping to securely engage the whole device within the well-casing, while the ratchet rings 31 engage with the threads 32 on the tubing 15a, the ratchet-rings 25 being of spring material and split for expanding sufficiently to pass over the threads while the plungers move to compressing position.

Naturally, an operator would wait a suitable 30 length of time after having sent the "go-devil" down, to allow for a proper operation of the packing material and wedges to firmly and securely engage with the well casing, before shearing the wire-line, by means of the shear-pin 27 from the placed bridge-plug.

After the bridge-plug has so been placed, and the wire-line been removed from the well, any work contemplated above the plug in the well may then be done.

After the work has been done, a working tubing 40 may be lowered into the well until the tubing engages with the threads 34 in the upper end of the handling-cap 23 and, by a simple right-hand turn of the working tubing, the spring 45 ratchet-rings 31 can be screwed along the threads 32 until the bridge-plug has been disengaged from the well-casing 11, when the whole bridge-plug may be withdrawn from the well in the well-known manner of withdrawing well-tools.

The threads 32 on the lower and upper ends 50 of the tubing 15a, of course, are left and right-hand, so that the right-hand turning of the working tubing, attached to the upper threads 34 of the cap 23, will operate in such a manner that the spring ratchet-rings 31 on the opposite sides and ends of the packing will properly unscrew, meaning that the lower ring would preferably be of left-hand threads and the upper ring would preferably be of right-hand threads. 55

In cases where any pressure medium existing 60 in a well is utilized, particularly, where cementing material or the like is to be passed through the central tubing 15 (15a), a sleeve-closure 36 is preferably provided, to close the conduits 28 65 after the packing and wedges have been set properly and before the cementing material or the like is allowed to pass through the tubing, in order to prevent such material from entering such conduits, or from entering the spaces behind the plungers 29, in order to assure a free operation of the plungers during the retrieving operation. This arrangement is roughly outlined in Fig. 5.

In order to eliminate, or avoid, any over-strong 75

impinging of the packing material and wedges upon the central tubing, a loose sleeve 35 is turnably inserted between the central tubing 15 (15a) and the packing material, so that a retrieving may be more readily accomplished without any great frictional resistance. This sleeve, of course, must be split, to facilitate placing this sleeve into the recess in the tubing as illustrated. However, after having been placed in that recess, 10 the split sleeve is preferably welded, or united, again into a solid ring-sleeve in order to prevent a crushing by the packing.

The spring ratchet-rings 31, on the other hand, remain split in order to be able to expand during 15 the compressing operation of the packing parts. In packed and compressed position, the spring rings are prevented from snapping off the threads 32 by the beveled edges 31, engaging with the beveled recess in such a manner as to be forced 20 into engagement with the threads. The spacing of the rings in the recesses allows the rings to get away from this forced position when moved in the opposite direction, or by the opposite ring-edges.

Having thus described my invention, I claim:

1. In a device of the class described, a center-tube, wedges slidably mounted on the center-tube, resilient sealing members co-operatively attached to the wedges, a structure partly enclosing the wedges so as to form pressure-receiving means to act on the enclosed wedge-portions, a container for holding a pressure medium disposed in the center-tube, communications between the inside of the center-tube and the pressure-receiving means, and means for releasing the pressure medium from said container to pass by way of the communications into the pressure-receiving means for actuating the wedges so as to expand the sealing member outwardly 40 against the inner walls of a well into which the device may be inserted.

2. In a device of the class described, a center-tube, a container holding a pressure medium within the passage of the center-tube, communications from the inside of the center-tube outwardly, a cylinder at the outer termination of said communications, wedges slidably mounted on the center-tube including portions movable in the cylinder, resilient sealing members co-operatively attached to the wedges, and means for releasing the pressure medium from the container against said portions of the wedges to act on the resilient sealing members.

3. In a device of the class described, a structure comprising a central compartment and outer cylinders with communications between the central compartment and the cylinders, a pressure medium in the compartment, means for releasing the medium into the cylinders, wedges axially 55 slidable over the structure with portions extending into the cylinders and adapted to be actuated by the pressure medium, and sealing means operatively engaged by the wedges for engaging with the side walls of a well when the pressure medium so actuates the wedges.

4. In a device of the class described, a structure comprising a compartment and outer cyl-

inders with communications between the compartment and the cylinders, a pressure medium held against escape within the compartment, means for releasing the medium into the cylinders, wedges slidable on the structure with portions extending into the cylinders and adapted to be actuated by escaped and released pressure medium, a packing means operative by the wedges for engaging with the side walls of and setting and holding the device at desired points in a well, and means for releasably lowering the device into the well.

5. In a device of the class described, a structure comprising a compartment and separate cylinder portions with communications between the compartment and the cylinder portions, a pressure medium held against escape within the compartment, means for releasing the medium into the cylinder portions, wedges in operative relation to the cylinders, a packing means operative by the wedges and adapted to engage with the side walls of and for setting the device at desired points in a well, and means for locking the device in such set position.

6. In a device of the class described, a structure comprising a compartment and separate cylinders with communications between the compartment and the cylinders, a pressure medium held against escape within the compartment, means for releasing the medium into the cylinders, wedges in operative relation to the cylinders, a packing means operative by the wedges and adapted to engage with the side walls of and for setting the device at desired points in a well, means for locking the device in such set position, and means for releasing the device from such set position.

7. In a device of the class described, a structure comprising a compartment and separate cylinders with communications between the compartment and the cylinders, a pressure medium held against escape within the compartment, means for releasing the medium into the cylinders, wedges in operative relation to the cylinders, a packing means operative by the wedges and adapted to engage with the side walls of and to set the device at desired points in a well, and means for detachably lowering the device by wireline into the well.

8. In a device of the class described, a structure comprising a compartment and separate cylinders with communications between the compartment and cylinders, a pressure medium held against escape within the compartment, means for releasing the medium into the cylinders, wedges in operative relation to the cylinders, a packing means operative by the wedges and adapted to engage with the side walls of and to set the device at desired points in a well, means for locking the device in such set position, means for releasing the device from such set position, means for detachably lowering the device into a well, and means for engaging the device to a working tubing for removing the device from the well.

CARL E. STROM.
